UNITED STATES PATENT OFFICE.

ABRAHAM J. HADDAD, OF JACKSON, MISSISSIPPI.

SAD-IRON.

1,010,361.

Specification of Letters Patent. Patented Nov. 28, 1911.

Application filed February 10, 1911. Serial No. 607,789.

To all whom it may concern:

Be it known that I, ABRAHAM J. HADDAD, citizen of the United States, residing at Jackson, in the county of Hinds and State of Mississippi, have invented certain new and useful Improvements in Sad-Irons, of which the following is a specification, reference being had therein to the accompanying drawing.

10 This invention relates to sad irons, and the principal object of the same is to provide a means whereby steam may be admitted to the interior of the iron and also to provide means so that when desired steam 15 may be admitted into a chamber where it can pass out through the bottom of the iron.

This invention is illustrated in the accompanying drawing, wherein—

Figure 1 is a view showing the iron ready 20 for use and having the steam conveying pipe connected with a steam generator indicated by dotted lines. Fig. 2 is a longitudinal sectional view through the iron. Fig. 3 is a plan view partly in section to expose the 25 inner chamber. Fig. 4 is a fragmentary view of the bottom of the iron. Fig. 5 is an enlarged fragmentary view of the end 30 of the pipe which admits steam into the inner chamber. Fig. 6 is a transverse sectional view through the pipe shown in Fig. 5.

Referring to the accompanying drawings it will be seen that this iron is intended to be used for pressing, and is intended to be connected with a steam boiler which is 35 shown in dotted lines in Fig. 1. This boiler may be of any desired construction, which is suitable for the use, the one shown being typical of any boiler. The iron 1 is connected to the boiler by means of a flexible 40 tube 2 which may be of any desired material such for instance as rubber. Steam passes from the boiler through the tube 2 and into the iron so that the iron is heated.

The iron comprises a perforated bottom 45 3 and the side walls 4, and back wall 5, the side walls being parallel for the greater portion of their length and being brought together at the front of the iron. The front 50 of the iron is reinforced by a thickened portion 6. The forward end of the iron is provided with an upstanding rim 7 which forms a front abutment for the cover 8, which is secured to the iron by means of screws 9

which enter sockets 10 formed in the thickened portion 6 and the upper end of the 55 rear wall 5. The rear wall has the upper portion reduced to form a ledge 11 which forms a support for the rear end of a dividing plate 12, the front end being supported by a brace 13. This plate 12 divides the 60 interior of the iron into an upper chamber 14 and a lower chamber 15.

The steam coil 16 is seated within the upper chamber 14 and has one end protruding through an opening formed in the rear wall 65 and the end of the flexible pipe 2 is secured to the protruding end 17 of the coil. The inner portion of the coil rests upon the plate 12 and extends along one side until it reaches the forward portion of the iron. The coil 70 is then coiled around as shown at 18 and extends along the opposite side of the iron as shown by the numeral 19 until it reaches the rear end of the iron. The pipe is then coiled again as shown by the numeral 20 75 and is brought forward between the two sections of the coil as shown by the numeral 21. The forward end of the coil communicates with a valve housing 22 which extends through an opening formed in the plate 12 80 and has its upper end provided with a flange 23 which rests upon the forward portion of the steam coil and is thus held in place.

The housing is provided with a central opening 24 which is enlarged at its lower 85 end to provide a shoulder 25. A valve stem 26 is slidably mounted within the housing 22 and has a washer 27 secured near its lower end which normally is held in contact with the shoulder 25 and thus prevents the steam 90 from passing out of the housing except when desired.

The cover 8 of the iron is provided with a housing 28 which is provided with an opening 29 which registers with the opening 95 through the housing 22 and into which the upper end of the valve stem 26 protrudes. The upper portion of the opening 29 is enlarged to provide a shoulder 30 which forms a bearing for the coil spring 31 which is 100 seated within the upper portion of the opening. A plunger 32 has its lower portion secured to the upper portion of the valve stem 26 and has its upper portion provided with an enlarged head 33 which rests upon the 105 upper end of the spring 31. This spring 31

normally holds the washer 27 in contact with the shoulder 25 and thus prevents the escape of steam through the opening 34 formed in the side of the housing 22 and 5 which is located adjacent the shoulder 25.

A pipe 35 is secured to the under surface of the plate 12 by means of the bolts 36 and has its neck portion 37 communicating with the opening 34 so that when the valve is 10 opened steam may pass through the opening 34 into the pipe 35. The pipe 35 is provided with a plurality of openings which are formed in its lower portion so that the steam may readily pass out through the 15 pipe and also that there will be no danger of water, formed from condensed steam, staying in the pipe and causing the same to rust. A cam lever 38 is pivotally mounted within the upper end of the housing 28 and 20 has its handle 39 extending toward the rear portion of the iron. The lever is provided with a lug 40 at its forward end which contacts with the front portion of the housing and prevents the lever from moving too far 25 forward. The handle 41 of the iron has its rear portion secured to a lug 42 formed near the rear end of the cover and has its forward portion secured to the housing 28. By examining Figs. 1 and 2, it will readily 30 be seen that the handle of the lever extends over the front portion of the handle of the iron so that the lever may be readily engaged by the thumb and pressed down so that the plunger is moved within the housing 35 against the tension of the spring 31, and will thus move the washer 27 away from the shoulder 25 and permit steam to pass through the opening 34.

In operation the steam passes through 40 the pipe 2 and into the steam coil and through the same until it enters the valve housing 22. By this means, the iron is heated and may be used, if desired, as an ordinary iron is. When it is desired to 45 press a coat or any other article, which ordinarily needs to be covered with a damp cloth, the valve is opened and steam is permitted to pass into the pipe 35. From here it passes out into the chamber 15 and 50 through the openings 43 formed in the bottom of the iron. By this means the cloth is dampened a sufficient amount and it is not necessary to use a damp cloth. The amount of steam which passes out through 55 the bottom of the iron may be regulated by the amount that the lever 39 is pressed down or, if desired, the valve may be opened only at intervals. It should be noted that the openings 43 are arranged in series and 60 run parallel with the longitudinal axis of

the iron. By this means there is prevented any friction when pressing.

What I claim is:—

1. In a device of the character described, a body portion, means for supplying fluid 65 to said body portion, said body portion being provided with a plurality of compartments, a pipe in one of said compartments, a perforated pipe in the other of said compartments, a valve connecting said pipes, 70 a handle secured to the top of said body portion, an operating mechanism for said valve, and a lever for operating said mechanism overhanging said handle.

2. A device of the character described, 75 comprising a body portion, means for conducting fluid to said body portion, a plate dividing said body portion into a plurality of compartments, a pipe within the upper one of said compartments, a pipe suspended 80 from the under surface of said plate, a valve connecting said pipes, a cover for said body portion, a housing formed upon said cover and communicating with said valve, a handle secured at one end to said cover and 85 at the other end to said housing, a plunger mounted within said housing, a valve stem passing through said valve and having its upper end secured to said plunger, and an operating lever pivotally connected with 90 said housing and overhanging said handle.

3. In a device of the character described, a body portion, means for conveying fluid to said body portion, said body portion being provided with a plurality of compartments, a pipe within one of said compartments, a valve housing resting upon said pipe and entering the second compartment, a pipe suspended within said second compartment and communicating with said 100 valve, a valve stem slidably mounted within said valve housing, a cover for said body portion, a housing formed upon said cover, and provided with an opening communicating with said valve housing, a spring within said cover housing, a plunger passing through said cover housing and secured to said valve stem, a cam lever pivotally mounted within said housing and resting upon said plunger and adapted to move said 105 plunger within said housing to open said valve, and a handle secured to said cover and overhanging said handle.

In testimony whereof I hereunto affix my signature in presence of two witnesses.
